Primary Examiner — Lauren D McVey*Assistant Examiner* — Sarah L Smith(74) *Attorney, Agent, or Firm* — Tarter Krinsky & Drogin LLP(57) **CLAIM**

The ornamental design for a water gun with rotatable nozzle, as shown and described.

DESCRIPTION

FIG. 1 is a side perspective view of the water gun with rotatable nozzle showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings depict environment and portions of the article which form no part of the claimed design.

1 Claim, 7 Drawing Sheets(56)
